VARIABLE PROPELLER

Forrest M. Kent, Spokane, Wash.

Application May 9, 1934, Serial No. 724,719

2 Claims. (Cl. 170—162)

My present invention relates to variable propellers and is an improvement over the device set forth in my copending patent application entitled "Variable pitch propellers", filed March

5 29, 1933, Serial No. 663,355, and also over the device embodied in my prior joint Patent No. 1,864,045, issued June 21, 1932 and entitled "Variable speed propellers." The principal objects of my present invention are to provide means

10 whereby the increase and decrease in the pitch of propeller blades is automatically caused by the pressure resistance of the water, or other medium, against the blades and is in direct proportion to the revolutions of the blades, and

15 whereby a rapid increase is caused in the momentum of the conveyance to which the device is attached.

With the above and other objects in view which will appear as the description proceeds, 20 the invention consists of the novel construction, adaptation, combination and arrangement of parts hereinafter described and claimed. These objects are accomplished by devices illustrated in the accompanying drawing; wherein:—

25 Figure 1 is a view in side elevation showing the device connected to the lower portion of an outboard motor; Fig. 2 is an enlarged view in rear end elevation of the device; Fig. 3 is a fragmentary view in transverse vertical section taken substantially on a broken line 3—3 of Fig. 6; Fig. 4 is a view in longitudinal vertical section taken on a broken line 4—4 of Fig. 2; Fig. 5 is a detail view in perspective of the hub block; Fig. 6 is a view in side elevation 30 of the device and showing the propeller blade pitch movement in dotted lines; and Fig. 7 is a detail view in perspective of the restraining collar.

35 Referring in detail to the drawing, the numeral 5 designates the lower portion of an outboard motor having a shaft 6 projecting rearwardly from its hub portion. A bushing or sleeve 7 fits snugly onto said shaft and a hub block 8 fits snugly onto said sleeve. A shear pin 9 passing through said block, sleeve and shaft, together with a nut 10 on the rear end of the shaft, retain said members securely in place. The forward end portion of the hub block is hollowed out by a chamber 11 which is closed 40 by a plate 12.

45 The hub block 8 has two opposite flat sides 13 upon which are seated the two flat inner T-ends 14 of propeller blades 15. Said flat inner ends are pivotally held by opposite screw bolts 16 extending through holes 17 therein and

threaded into the hub block where set screws 18 hold them in place. Screw pins 19 are threaded through the flat T-ends of the propeller blades and pass loosely through arcuate slots 20 in the hub block with their inner pin ends projecting into the chamber 11. The arcuate slots are concentric with the screw bolts 16 so that, when the T-ends of the propeller blades are pivotally moved they will move the screw bolts back and forth in the arcuate slots. Set screws 21 may project through the hub block into communication with each end of the arcuate slots and into engageable relation with the screw pins whereby the pivotal movement of the propeller blades may be adjustably regulated

5

15

as will be understood. The inner pin ends of the two screw pins 19 extend through holes in eyelet bearings 22 that are secured to a restraining collar 23 that is mounted on the bushing 7 of the shaft 6 within the chamber 11. A coiled spring 24 is also mounted on said bushing within the chamber and has one of its ends fixed to the hub block 8. The other end of said spring may be connected to the collar 23 or to one of the eyelets 25 22. This spring is so arranged and tensioned as to normally retain the propeller blades 15 at a low or reduced pitch as shown in dotted lines in Fig. 6 of the drawing. It will be understood that the foregoing described connection between the T-ends of the propeller blades and the collar 23, namely the screw pins 19 and eyelets 22, causes the propeller blades to pivotally move in unison.

30 Referring particularly to Fig. 2 in describing the operation of the device, it will be noted that the screw bolts 16 about which the propeller blades pivotally move are diametrically opposite each other with respect to the center of the hub block 8 and shaft 6. A line, such as the 35 broken line 4—4, projected centrally through said screw bolts and shaft will therefore represent the axis about which the propeller blades pivotally move. This line will divide the respective propeller blades into diametrically opposite 40 major portions X and minor portions Y. In other words, the two blades are eccentrically mounted with respect to each other, and this is a very important feature of the invention.

45 When the device rotates in a counter clockwise direction, as indicated by the direction arrow in Fig. 2, the major portions X will be the leading portions of the blades and will engage the water in advance of the minor portions Y. A greater pressure resistance will therefore be 50 55

exerted on these leading major portions thus creating a torque which will cause the blades to pivotally move on their respective axes and overcome the resistance of the spring 24 where-
5 by the pitch of the propeller blades will be in-
creased. This increase of the pitch will cause the conveyance on which the device is installed to gather momentum very rapidly and is entire-
ly automatic and in direct proportion to the in-
10 crease in the revolutions of the propeller blades. In other words, an increase in the revolutions of the propeller blades causes a corresponding increase in pressure resistance against the lead-
ing major portions of the blades and a like in-
15 crease in the pitch of the blades. The pitch of the blades may thus be increased from the minimum, as shown in dotted lines in Fig. 6, to the maximum as shown in full lines, and the spring 24 will cause the blades to return to their mini-
20 mum pitch when the rotary movement of the blades ceases.

Having thus described my invention, what I claim and desire to secure by Letters Patent of the United States is:—

25 1. A variable propeller comprising a shaft, a hub block fixed on the shaft, said hub block having a hollow chamber, two opposite flat sides, and an arcuate slot extending through each flat side into the chamber, a pair of propeller blades
30 having flat inner T-ends respectively seated on the two opposite sides of the block, pivotal connections that are diametrically opposite to each other and concentric with the arcuate slots con-

necting the T-ends of the propeller blades to the block in such position that the centers of the propeller blades are offset with respect to each other, screw pins respectively connected to the T-ends and extending slidably through the arcuate slots into the chamber of the block, a collar mounted on the shaft within said chamber, a pair of opposite eyelet bearings pivotally connected to the collar, said screw pins extending through said eyelet bearings, and a coiled 10 spring mounted on the shaft within the chamber and having one of its ends connected to the hub block and its other end connected to the collar.

2. A variable propeller comprising a shaft, a 15 hub block fixed on the shaft and having a hollow chamber, two opposite flat sides, and an arcuate slot extending through each flat side into the chamber, a pair of propeller blades pivotally connected to the flat sides of the hub block 20 in opposite offset relation to each other, screw pins respectively connected to the propeller blades and extending slidably through the arcuate slots into the chamber of the block, a collar mounted on the shaft within said chamber, a 25 pair of opposite eyelet bearings pivotally connected to said collar, said screw pins extending through said eyelet bearings, and a coiled spring mounted on the shaft and having one of its ends connected to the hub block and its other 30 end connected to the collar.

FORREST M. KENT.
